COMBINED CLEARANCE AND MARKER LAMP LENS

Robert I. Nagel, Skokie, Ill., assignor to Dominion Auto Accessories Limited, Toronto, Ontario, Canada

Filed Jan. 2, 1974, Ser. No. 430,198

Term of patent 14 years

Int. Cl. D26—08

U.S. Cl. D48—32 A

FIG. 1 is a plan view of a combined clearance and marker lamp lens embodying my design.

FIG. 2 is an end elevational view of the same.

FIG. 3 is a side elevational view of the same.

FIG. 4 is a sectional view taken along the line 4—4 in FIG. 1.

FIG. 5 is a sectional view taken along the line 5—5 in FIG. 1.

I claim:

The ornamental design for a combined clearance and marker lamp lens, as shown.
